ATTORNEY

UNITED STATES PATENT OFFICE.

JULIUS BRENZINGER, OF FAIRFIELD, CONNECTICUT, ASSIGNOR TO THE MAX AMS MACHINE COMPANY, OF BRIDGEPORT, CONNECTICUT, A CORPORATION OF CONNECTICUT.

SEAMING MACHINE.

Application filed April 7, 1922. Serial No. 550,311.

To all whom it may concern:

Be it known that I, JULIUS BRENZINGER, a citizen of the United States, and a resident of Fairfield, in the county of Fairfield and 5 State of Connecticut, have invented certain new and useful Improvements in Seaming Machines, of which the following is a specification.

This invention relates to seaming machines of the type disclosed in Letters Patent No. 836,735 of November 27, 1906 (Reissue No. 12,668 of July 2, 1907) in which there is employed a seaming roller or tool having an outline complementary to that of a non- 15 circular container to be seamed.

In seaming the covers or tops to non-circular containers, such as a rectangular shaped container with rounded corners, difficulty has been experienced when seaming the 20 corners because the metal at that point is not merely curled up and flattened as at the straight sides of the container but is also compressed or crowded together owing to the fact that the metal occupies a smaller 25 arc of a circle after, than before, seaming. For this reason buckling or wrinkling of the metal is likely to take place.

The main object and feature of this invention is to overcome this difficulty.

30 In the accompanying drawings the invention is disclosed in a concrete form in which—

Fig. 1 is a plan view of a seaming roller or tool embodying the invention, showing 35 its relation to a container while seaming said container at the corner thereof.

Fig. 2 is an edge view thereof.

Fig. 3 is a sectional view on the line 3—3 of Fig. 1.

40 Fig. 4 is a sectional view on the line 4—4 of Fig. 1.

1 indicates the seaming roller or tool by means of which the entire seaming operation may be carried out, but preferably the initial curling operation only is produced by this roller. 2 indicates a non-circular container to which a cover 3 is to be seamed. As shown, the roller is of a shape complementary to that of the container, as fully 50 explained in the patent previously referred to. This roller is provided with a seaming

surface having portions 4 of the contour shown in Figs. 2 and 4 intended to act on the straight sides of the container. As will be observed the initial curl 5 produced thereby, prior to the flattening operation, is relatively large. If it is attempted to produce a similar curl at the corner of the container the metal is likely to buckle or wrinkle because it will occupy a smaller arc after, than 60 before, seaming. I therefore find it advantageous to provide the seaming surface of the roller with portions, as 6, of a different contour from that of portions 4. As shown, portions 6 are narrower and are so shaped 65 as to produce a smaller initial curl 7 so that when the metal is thereafter flattened it will not wrinkle. Portions 4 and 6 alternate lengthwise of the seaming surface and gradually merge into one another as shown in 70 Fig. 2.

I claim:

1. A seaming roller, having an outline complementary to that of the outline of a non-circular container, provided with a 75 seaming surface of different dimensions at different portions of its length to thereby produce a different seaming action at the corners of the container than at the sides thereof. 80

2. A seaming roller, having an outline complementary to that of the outline of a non-circular container, provided with a seaming surface having portions, acting on the seam at the straight sides of the container, of a certain contour, and other portions, acting on the seam at the corners of the container, of a different contour. 85

3. A seaming roller, having an outline complementary to that of the outline of a non-circular container, provided with a seaming surface having portions, acting on the seam at the straight sides of the container, of a certain contour to produce a certain initial size of curl, and other portions, 90 acting on the seam at the corners of the container, of a different contour to produce a certain smaller initial size of curl. 95

Signed at New York, in the county of New York and State of New York, this 4th day of April, 1922.

JULIUS BRENZINGER.
